UNITED STATES PATENT OFFICE.

HENRY C. HARRISON, OF NEW YORK, N. Y., ASSIGNOR TO WESTERN ELECTRIC COMPANY, INCORPORATED, OF NEW YORK, N. Y., A CORPORATION OF NEW YORK.

RECEIVER.

1,352,597.

Specification of Letters Patent. Patented Sept. 14, 1920.

Application filed October 23, 1918. Serial No. 259,365.

To all whom it may concern:

Be it known that I, HENRY C. HARRISON, a citizen of the United States, residing at New York, in the county of New York, 5 State of New York, have invented certain new and useful Improvements in Receivers, of which the following is a full, clear, concise, and exact description.

This invention relates to telephone receivers for general use in telephone or signaling circuits and has for its object to provide a receiver with an improved magnetic structure and one having its parts so proportioned and arranged as to provide an instrument of high sensitivity in responding to the feeble alternating currents such as those generated by voice waves impinging upon the diaphragm of a telephone transmitter.

20 More specifically, the object of this invention is to provide a telephone receiver having its magnetic structure so arranged as to provide a path of low reluctance for the flux generated by the alternating or voice currents, and therefore capable of operating efficiently and without causing undue distortion in the voice current wave forms.

To attain this object, the invention consists of certain new and novel features in 30 the construction as will be more fully described and particularly pointed out in the appended claims.

In the accompanying drawings, Figure 1 is an enlarged view in perspective of the 35 magnetic structure of the receiver embodying this invention: Fig. 2 is an inverted plan view partly in section of the receiver shown in Fig. 1; and Fig. 3 is a diagrammatic view of the magnetic circuit of receiver 40 shown in Fig. 1.

Referring now to the drawing, there is shown the magnetic structure of a receiver of the customary watch-case type. The permanent magnet 5 which is semi-circular in 45 shape is provided at its ends with inwardly and upwardly extending polar extensions 6 and 7 which are secured in place by means of the screws 8-8. The free ends of members 6 and 7 are trifurcated to provide two sets of pole pieces 9, 10 and 11, and 12, 13 and 14. The outer pole pieces 9, 11, 12 and 14 are bent outwardly and formed to lie in a circle. The inner pole pieces 10 and 13 are bent inwardly and provided with energizing windings 15 and 16, respectively.

Securely fastened to the receiver diaphragm 17 is a cup-shaped magnetic member 18, the wall 19 of which lies outside of the pole-pieces 10 and 13 but inside of the pole pieces 9, 11, 12 and 14. The talking windings 15 and 16 are connected in series and in such a manner that current flowing through the windings in a given direction will make the poles 10 and 13 of opposite polarity. This is represented in Fig. 3 of the drawing by marking pole 10 with a "+" sign and pole 13 with a "-" sign as showing the direction of flux at a given instant resulting from voice currents traversing the windings in the direction indicated by the small arrows. 70

With current flowing through the windings in the direction as designated, the operation of the receiver will be easily understood by an examination of the magnetic circuits. The main path for the polarizing 75 flux is from pole 10 across the air-gap to cup member 18, thence across the air-gap to pole piece 13 and back to pole 10 through polar extension 7, magnet 5 and polar extension 6. Parallel paths are also provided 80 from poles 9 and 11 to the wall portion 19 and from the wall portion 19 to poles 12 and 14. Since the direction of flux across the air-gaps in these paths is radial there is no force exerted tending to cause movement of 85 the receiver diaphragm.

The paths for the flux generated by voice currents flowing through the talking windings 15 and 16 with the direction of current as indicated are as follows:

(1) From pole 10 across the air gap to cup-member 18, to wall portion 19, thence across the air-gaps in parallel to poles 9 and 11 and back to pole 10. 90

(2) From pole piece 13 to pole pieces 12 95 and 14, thence across the air-gaps in parallel to the wall portion 19, cup-member 18 and across the air-gap to pole 13.

(3) From pole piece 10 across the air-gap to cup-member 18, across the air-gap to 100 pole 13, through polar extension 7, permanent magnet 5 and polar extension 6, back to pole 10.

The reluctance of the latter path, however, is so high to alternating currents of 105 voice frequency that the flux will tend to leak across between the polar extensions rather than to pass through the permanent magnet. With the above paths for the polarizing flux resulting from the permanent 110

magnet and the alternating flux generated by the voice currents at a given instant, it will be noted that the flux from the talking winding is in a direction to augment the 5 polarizing flux passing from pole 10 to cup-member 18 and from the cup-member to pole 13, thus increasing the pull on the diaphragm 17. The flux from the talking winding passing from the wall portion 19 10 of cup-member 18 to poles 12 and 14 wall portion 19 is in a radial direction and therefore does not affect the pull on the diaphragm. With the current flowing through the talking windings in the opposite direction, the flux from the talking windings 15 is in a direction to oppose the polarizing flux passing across the air-gaps from the pole 10 to the cup-member 18 and from the cup-member to pole 13. The flux from the 20 talking windings passing from poles 9 and 11 to the wall portion 19, to cup-member 18 and from the wall portion 19 to poles 12 and 14 is in a radial direction as in the previous case, and, therefore, does not affect 25 the pull on the diaphragm 17.

The outer poles 9, 11, 12 and 14 in combination with the wall portion 19 of cup-member 18, provide low reluctance return paths for the alternating currents. Because of the relatively large air-gaps existing between poles 9, 11, 12 and 14, and the diaphragm 17, the latter, if of magnetic material is not affected appreciably by flux passing through these poles. However, in this design it is not essential that the diaphragm itself be of magnetic material, since the cup-member can be proportioned to satisfactorily carry the flux generated. Because of the low reluctance return paths provided for the alternating current flux generated by the voice currents the magnetic structure embodying this invention provides a receiver of high sensitiveness. A further advantage of the low reluctance return paths for the alternate current flux is the lesser tendency for the receiver to be demagnetized.

What is claimed is:

1. A telephone receiver comprising a permanent magnet, a pair of trifurcated polar extensions secured to the ends thereof, a magnetizing winding for each of said polar extensions, and a diaphragm in operative relation with the middle trifurcations of said polar extensions, but so disposed with respect to the outer trifurcations of said polar extensions as not to be effected by magnetic flux passing therethrough.

2. A telephone receiver comprising a permanent magnet, a polar extension secured to the magnet at each end, the free end of each polar extension being formed to provide three pole pieces, a magnetizing winding on the middle pole piece of each extension, and a diaphragm in operative relation

with said middle pole pieces but so disposed with respect to said other pole pieces as not to be affected by magnetic flux passing therethrough.

3. A telephone receiver comprising a permanent magnet, a pair of inwardly extending polar extensions secured thereto, the free end of each polar extension being formed to provide three pole pieces, a magnetizing winding on the middle pole piece of each extension, said windings being connected in series, and a diaphragm in operative relation with the middle pole pieces of said polar extensions, but so disposed with respect to said other pole pieces as not to be affected by magnetic flux passing therethrough.

4. A telephone receiver comprising a permanent magnet, a trifurcated polar extension so formed as to provide three pole pieces secured to each end of said magnet, the middle pole piece of each extension being formed to lie inside of the outer pole pieces, a diaphragm, and a magnetic cup-shaped member secured to the diaphragm and in operative relation with said pole pieces.

5. A telephone receiver comprising a semi-circular permanent magnet, a polar extension secured to each end of the magnet, the free end of each of said polar extensions being formed to provide three pole pieces out of line with each other, a magnetizing winding secured on the middle pole piece of each extension, a diaphragm, and a cup-shaped member secured to the diaphragm and in operative relation with said pole pieces, said member having a wall portion adapted to encircle the inner pole pieces and lie inside of the outer pole pieces.

6. A telephone receiver comprising a pair of trifurcated polar extensions, means for establishing a constant magnetic potential between said polar extensions, means for establishing varying magnetic potentials between said polar extensions, and a diaphragm in operative relation with the middle trifurcations of said polar extensions, but so disposed as not to be affected by the magnetic flux passing through the outer trifurcations of the polar extensions.

7. A telephone receiver comprising a plurality of pole pieces having a magnetizing winding thereon, a diaphragm in operative relation to said pole pieces, means for impressing a constant magnetomotive force on said pole pieces, means for impressing a variable magnetomotive force on said pole pieces, and a plurality of additional pole pieces adapted to provide return paths for the flux generated by said magnetizing windings and so disposed as to exert no pull upon said diaphragm.

8. A telephone receiver comprising a plurality of pole pieces having a magnetizing

winding thereon, a diaphragm having a magnetic extension member in operative relation to said pole pieces, means for impressing a constant magnetomotive force on said pole pieces, means for impressing a variable magnetomotive force on said pole pieces, and a plurality of additional pole pieces adapted to provide return paths for the flux generated by said magnetizing windings but so disposed as to exert no pull upon said diaphragm.

9. A telephone receiver comprising a plurality of pole pieces having a magnetizing winding thereon, means for impressing a constant magnetomotive force on said pole pieces, means for impressing a variable magnetomotive force on said pole pieces, a plurality of additional pole pieces adapted to provide return paths for the flux generated by said magnetizing windings, a diaphragm, and a magnetic cup-shaped member attached to the diaphragm, said cup-shaped member being provided with right-angle portions extending between said first pole pieces and said second pole pieces to provide a return path for alternating current flux in a direction which does not exert any pull upon the diaphragm.

extending between said first pole pieces and said second pole pieces.

10. A telephone receiver comprising a plurality of pole pieces having a magnetizing winding thereon, means for impressing a constant magnetomotive force on said pole pieces, means for impressing a variable magnetomotive force on said pole pieces, a plurality of additional pole pieces adapted to provide return paths for the flux generated by said magnetizing windings, a diaphragm, and a magnetic cup-shaped member attached to the diaphragm, said cup-shaped member being provided with right-angle portions extending between said first pole pieces and said second pole pieces to provide a return path for alternating current flux in a direction which does not exert any pull upon the diaphragm.

In witness whereof I hereunto subscribe my name this 18th day of October A. D. 1918.

HENRY C. HARRISON.
